UNITED STATES PATENT OFFICE

WILLIAM FREDERIC CANAVAN, OF MONTREAL, QUEBEC, CANADA

SAFETY CLOSURE FOR WALL OPENINGS

Application filed September 1, 1927. Serial No. 216,992.

The invention relates to an operating mechanism for wall opening closures, as described in the present specification and illustrated in the accompanying drawings that form part of the same.

The invention consists essentially of the novel features of construction pointed out broadly and specifically in the claims for novelty following a description containing an explanation in detail of an acceptable form of the invention.

The objects of the invention are to facilitate the opening and maintaining the window in an open position following undue pressure from the inside, such as dust explosions in elevators and other unforeseen occurrences by the abnormal increase of atmospheric volume resulting in the forcible throwing open of the window; to insure efficient working of the parts through the effective leverage employed in the gripping of the window sash; to eliminate the difficulties incident to holding the window sash in an extreme open position; to furnish this mechanism at a reasonable cost to the consumers and insure the continuity of the safety features; to add improved constructional features to the device patented in United States under No. 1,479,452, on January 1st, 1924; and generally to provide a reliable, durable and serviceable device readily operated in groups or singly and applicable under many and sundry conditions.

In the drawings, Figure 1 is a perspective view, showing the mechanism apart from the window.

Figure 2 is a side elevational view of a window sash showing the application of the mechanism.

Figure 3 is an inside elevational view of a plurality of sashes operated by the mechanism.

Figure 4 is a cross sectional detail showing the clamping feature in securing the lever mechanism to the ratchet wheel.

Figure 5 is a longitudinal sectional view of the levers, showing the disengagement of the pawl from the ratchet in the extreme open position of the window.

Figure 6 is a perspective view showing the mechanism for individual wall openings.

Like numerals of reference indicate corresponding parts in the various figures.

Referring to the drawings, the tripod arms 10, 11 and 12 project outwardly from the window sash 13 and are secured at their ends 14 and 15 intermediate of the height of the sash end at the end 16 to the lower sash bar approximately in the centre. The arms 10 and 11 are angle bars and the arm 12 is secured therebetween at the angles 17 and the said arms extend outwardly from the window in the parallel extensions 18 and 19.

The pivotal bars 20 and 21 are pivotally secured to the ends of the parallel extensions 18 and 19.

The lever 25 is pivotally secured to the end 24 of the connecting rod 20 and is rigid with clamp section 26 mounted on the shaft 27, the other clamp section 28 being also mounted on the shaft 27 and drawn to the section 26 by the bolts 29 and nuts 30 pressing on the spring washers 31 to the desired friction pressure on the ratchet wheel 32 and particularly on the circular bosses 33 and 34 in the recesses 35 and 36 in the said sections 26 and 28 respectively, said ratchet wheel being driven on the key 37 in said shaft 27.

The section 26 is formed with a bracket extension 38, and an inwardly extending flange 39 from the extreme upper end of the bracket under which the head 40 of the pawl 41 is held to engagement with the ratchet wheel 32, said pawl being mounted on the pivot 42 secured in said bracket extension. The tail 43 of the pawl 41 extends rearwardly under the strap 23 and is depressed by said strap when the sash is fairly wide open thereby releasing the pawl from its engagement with the ratchet wheel, thereby stopping the window from further opening.

The handle 48 for individual operation may also be attached and used when desired, but in large installations the shaft 27 extends for a considerable distance and is journaled in the bearings 49 and operated by the worm and gear mechanism 50 and hand wheel 51.

For single operation the shaft 27 is preferably fixed between the brackets 22 and the clamp sections 26 and 28 which operate the lever 25 and the pivotal bars 20 and 21.

through the pawl 41 which engages with the ratchet wheel 32 fixedly secured to the shaft 27.

Briefly the operation of this invention is as follows:—

The operating shaft usually is common to a number of window sashes and carries a corresponding number of ratchets. These ratchets are keyed to the operating shaft and the levers are mounted on the shaft and frictionally engage the ratchets, that is to say, they are clamped to said ratchets, firmly enough to hold the sashes in the open positions.

In so far as the engagement of the ratchets through the spring-held pawls is concerned, these pawls do not leave the ratchets at all, the sashes may be blown open and the result of this is that the pawls drag from tooth to tooth over the ratchets until the open position is reached, and in that position the ratchet holds the sash outwardly and upwardly.

In returning the sash to its closed position, the shaft is operated and the ratchet pushes against the pawl continually until the sash reaches its closed position, consequently there is no release of the pawl at all from the ratchet. This is shown and described in my earlier Patent No. 1,479,452, and broadly claimed therein.

In the present invention there is no intention to claim as novel the ratchet and pawl mechanism for permitting the sashes to swing to their open positions automatically following an explosion, but rather to claim the frictional means, whereby each sash may be operated individually and held to its position by means of the frictional contact of the lever with the ratchet, and as well the means employed for engaging the window sash and supporting it by the lever link and sash arms. The connection of the sash supporting arms, the pivotal rod and the frictionally held lever must be emphasized in the present invention, as the means employed for perfecting the invention described and shown in Letters Patent No. 1,479,452 granted to me on the first of January 1924.

What I claim is:—

1. In operating mechanism for wall opening closures, a closure frame, a bracket utilized in bodily lifting and lowering said frame and having a plurality of arms spread to grasp said frame at the bottom and intermediately, an operating lever and connecting rod pivotally secured to said bracket, a pawl pivotally secured in said lever and a ratchet suitably mounted and frictionally held in said lever.

2. In operating mechanism for wall opening closures, a closure frame, a supporting bracket secured to said frame, an operating shaft and ratchet mounted thereon, a housing for said ratchet having side plates adapt-

ed to engage and brake said ratchet and a lever extension from said housing pivotally connected to said bracket and a spring-held pawl secured to said housing and engaging said ratchet.

3. In operating mechanism for wall opening closures; a window sash, a bracket having three supporting legs, one leg being secured to a horizontal sash bar, and the other leg to upright bars, a lever linked to said bracket carrying a spring-held pawl and extending to form a shaft bearing, an operating shaft journalled in said bearing, a ratchet fixedly mounted on said shaft adjacent to said extension, and a plate secured to said extension so and bearing on said ratchet.

4. In operating mechanism for wall opening closures, a window sash, a bracket having a spread of legs secured to said sash respectively at the bottom and intermediately and converging to a pivot bearing, a lever carrying a spring held pawl and forming a ratchet enclosure, a link pivotally joining said arms and said lever and having an offset forming a stop, and an operating shaft and a ratchet in constant engagement with said pawl, said lever holding said ratchet in constant frictional contact.

5. In operating mechanism for wall opening closures, a window sash adapted to be bodily lifted to a horizontal position, a bracket having spreading arms secured to said sash, an operating shaft and a ratchet fixedly mounted thereon, a lever having a removable plate adjustably secured thereto in contact with said ratchet at a predetermined pressure, a pawl carried by said lever and spring-held to said ratchet, a connecting rod in split sections pivotally joining said lever and said bracket and an operating handle secured to said lever for individual operation.

Signed at Montreal, Canada, this 25th day of August 1927.

WILLIAM FREDERIC CANAVAN.
